UNITED STATES PATENT OFFICE.

EARL V. WILLIAMS, OF KOKOMO, AND EVERETT C. WILLIAMS, OF GALVESTON, INDIANA.

OIL BURNER.

Application filed August 23, 1921. Serial No. 494,481.

To all whom it may concern:

Be it known that we, EARL V. WILLIAMS and EVERETT C. WILLIAMS, citizens of the United States, residing at Kokomo, in the county of Howard and State of Indiana, and Galveston, Cass County, Indiana, respectively, have invented certain new and useful Improvements in Oil Burners, of which the following is a specification.

10 This invention relates to liquid fuel stoves, and has for one of its objects to provide a simply constructed attachment whereby the creation of smoke and like products of combustion is prevented and the stove 15 rendered practically smokeless and free from odors.

With these and other objects in view the invention consists in certain novel features of construction as hereinafter shown and 20 described and then specifically pointed out in the claim, and in the drawings illustrative of the preferred embodiment of the invention:—

Figure 1 is a side elevation of a liquid 25 fuel stove with the novel attachment applied.

Figure 2 is a section on the line 2—2 of Fig. 1.

Figure 3 is a plan view enlarged, of a 30 part of the apparatus with the chimney member in section on the line 3—3 of Fig. 2.

Figure 4 is a bottom plan view enlarged of the combined flame ring and chimney support.

35 Figure 5 is an enlarged sectional detail illustrating the construction more fully.

The improved attachment may be applied to various forms of liquid fuel stoves without material change, and it is not desired to 40 limit the invention in this respect, but for the purpose of illustration the improved attachment is shown applied to a conventional stove of the above noted class in which 10 and 11 represent the outer and inner wick tubes which support the wick 12 between them and with an outwardly directed flange 13 intermediate the ends of the outer tube.

The burner tubes 10 and 11 are supported 50 upon the fuel feed tube 14 and enclosed in a casing 15, the latter in turn, carrying the grate or grill 16 for supporting the cooking utensils in the ordinary manner.

Extending inwardly from the inner wick 55 tube 11 are supporting wires 17 on which the inner tube 18 of the spreader device 20

is engaged by bayonet slots 19. By this means the spreader device is supported in position relative to the wick tube as shown, and can be readily detached by simply partially rotating the spreader and moving it upwardly.

Encompassing the outer wick tube 10 is a flame ring 21 including an inwardly directed upper portion approaching the upper 65 edge of the outer wick tube, and producing a restricted passage for the upwardly moving air externally of the wick.

At its lower edge the member 21 is formed with an encompassing outwardly directed 70 flange 22 to support an endless band 23, the latter extending at its upper edge above the line of the flame, as shown.

Directed inwardly from the flame ring 21 are a plurality of lugs 24 bearing at their 75 inner ends upon the flange 13 of the outer burner tube. By this means the flame ring is maintained in position and uniformly spaced from the wick tube.

The chimney portion of the improved 80 device is represented as a whole at 25 and includes an inwardly directed annular top member 26.

At its lower edge the chimney member 25 rests upon an annular member comprising 85 an outer chimney supporting flange 27, an inner downwardly directed flange or rim 28, and an upwardly extending intermediate portion 29, the latter portion having a plurality of air intake apertures 30.

The annular member is so proportioned 90 that the elevated portion 29 with its perforations 30 is disposed above the line of the lower edge of the spreader 20, or above the line of the lower part of the flame from 95 the wick, so that air entering through the apertures comes in contact with the flame just as it passes over the spreader, and thus supplies fresh oxygen to instantly consume any particles of unconsumed carbon or 100 other products of the combustion, and thus effectually prevent the creation of smoke or gases and renders the burner smokeless and odorless.

Attached to the chimney 25 and the supporting flange 27 of the annular member is a handle device 31 to enable the chimney and its annular member to be tilted upon the edge of the member 23 opposite to the handle, when the burner is to be lighted.

110 The wick adjusting device is indicated at 32 and is of the usual form.

By this simple arrangement a supply of fresh air is supplied to the flame at the point where the smoke is usually generated and where the unconsumed gases escape, and thus instantly produce a supplemental or secondary combustion of the unconsumed combustible gases, carbon particles and the like which produce the smoke, and render the burner smokeless and odorless.

10 This simply constructed device may be made of any required size or capacity and operates successfully for the purposes described.

Having thus described the invention what 15 is claimed as new is:—

An attachment for liquid fuel stoves hav-

ing an annular burner element formed of outer and inner tubular members with the outer tubular member extending above the line of the inner tubular member, a flame 20 ring encompassing the burner element and spaced therefrom, with its upper line slightly above the upper line of the outer tubular member of the burner element, a chimney device, a draft ring carried by 25 the chimney, and means for supporting the chimney with the draft ring above the line of the flame of the burner element.

In testimony whereof, we affix our signatures hereto.

EARL V. WILLIAMS.
EVERT C. WILLIAMS.
